2,472,716

SPANNER WRENCH WITH WORK-
RETAINING LOOP

Frank G. Miller, Farmingdale, and Leslie S. Bogert, Richmond Hill, N. Y., assignors to Republic Aviation Corporation, Farmingdale, N. Y., a corporation of Delaware

Application February 27, 1945, Serial No. 579,960

3 Claims. (Cl. 81—90)

1

This invention relates to a wrench of the spanner type designed to operate on the separable components or elements of a unitary structure or mechanism, whereby each component or element may be individually engaged by one of the present wrenches and be thereby manipulated or adjusted with respect to its complemental component or element for the assembly or dismantling of said unitary structure or mechanism.

Among its other objects the instant wrench proposes a tool, which, while primarily intended for the assembly or dismantling of the components or elements of unitary structures or mechanisms, such as, for example, an accumulator, may be employed to engage and manipulate relatively large structures of unusual shapes as distinguished from the customary and standard elements usually engaged and manipulated by spanner wrenches.

This invention also contemplates a wrench which may be easily and quickly applied to or removed from the structure to be engaged and manipulated thereby, and yet have such a firm, strong and operative engagement therewith that the lifting, supporting and transportation thereof by and with the wrench may be accomplished with no likelihood of accidental or unintentional displacement of the wrench from its cooperation with the engaged structure.

With the above and other objects in view, as will be apparent, this invention consists in the construction, combination and arrangement of parts all as hereinafter more fully described, claimed and illustrated in the accompanying drawings, wherein:

Fig. 1 is an elevation of one side of a wrench constructed in accordance with the present invention;

Fig. 2 is a similar view from the opposite side thereof;

Fig. 3 is a central longitudinal section through the wrench taken along line 3—3 of Fig. 2;

Fig. 4 is a section taken along line 4—4 of Fig. 3 to illustrate the construction of the joint between the loop or engaging member of the wrench and its handle;

Fig. 5 is a perspective view of the filler which spaces and braces those portions of the loop or engaging member adjacent the handle to prevent distortion or bending thereof under operating conditions;

Fig. 6 is an edge elevation of a pair of wrenches constructed in accordance with the present invention, each cooperating with one of the components or sections of an accumulator; and

2

Fig. 7 is a view at right angles to Fig. 6 to illustrate the relative cooperation of a pair of companion or complemental wrenches in the assembly or dismantling of an accumulator.

While the present wrench may be of general application and use in the engagement and manipulation of elements or structures of large and unusual shapes, it is especially designed for the servicing of aircraft accumulators. These accumulators are frequently spherical in shape and are almost always relatively large and awkward to handle and customarily comprise a pair of complementary sections or components which, in assembly or dismantling, must be relatively rotated to operate the interengaging threads or other fastening means on the several sections by which the components are secured one to the other. Because of the size and hemi-spherical shape of each of the sections or components of the accumulator, difficulty has been experienced in engaging and handling the two halves for the assembly and dismantling of the accumulator. Since accumulators require constant attention and service, the difficulty of dismantling and the reassembly thereof becomes an ever present problem, for the solution of which no satisfactory tool adapted to engage each of said components for its manipulation have been heretofore provided.

Furthermore once the accumulator has been dismantled by the separation of its components or hemi-spherical halves, no tool or means has heretofore been provided by which the accumulator section or half can be held, handled, transported, or otherwise manipulated. By providing a stable engagement between its handle and the engaged accumulator half, the instant invention in addition to functioning as a wrench in the assembling or dismantling of the accumulator, also serves as a handle by which it can be readily and conveniently manipulated, handled or transported.

The present tool is designed especially for the purpose of engaging one hemi-spherical half of an accumulator so that, by the use of a pair of these tools or wrenches, the several components or sections of the accumulator may be individually engaged and be rotated relatively for assembly or dismantling of the accumulator.

Reference being had more particularly to the drawings, 10 designates the engaging member of the wrench which consists of a single unitary section of metal, either round or polygonal in cross section, bent into a loop which will, as herein-after more fully described, circumscribe and engage over a section or half of the accumulator to

rest flush against the flange 30 thereof. The extremities 10' of this section of metal are positioned to lie in close juxtaposition, parallel one to the other whereby they constitute means by which a handle is secured to the engaging member or loop 10.

Diametrically opposed to the terminals 10' is a lug 11 laterally projecting from and secured to the loop or engaging member 10 in any suitable manner, as, for example, by welding. This lug 11 terminates in an angularly disposed gripping flange 12 positioned parallel to and spaced from the body of the loop or engaging member 10. On the same face of the loop or engaging member 10 as that from which the lug 11 projects are secured a series of spaced, engaging pins 13. These pins 13 may be formed integrally with the loop or engaging member 10, or, as illustrated, be imbedded therein at their inner ends. In any event they are parallel one to the other and project from the surface of the loop 10 a distance approximately equal to the length of the lug 11 between the loop 10 and the engaging flange 12.

A handle 14, having a hollow inner end portion 15, cooperates with the ends 10' of the loop 10 by the embracing and engagement thereof within said end portion 15. The inner end 15 of the handle is permanently secured to the extremities 10' of the loop or engaging member 10 in any suitable manner, preferably by welding. When the extremities 10' of the loop or engaging member 10 are received in and secured to the end section 15 of the handle 14, the loop 10 and the handle 14 become, to all intents and purposes, a single unitary structure. To brace the loop or engaging member 10, where it joins the handle 14, a filler 16 is inserted between the reversely curved portions 10'' of the loop or engaging member adjoining the handle 14. This filler has a comparatively wide end 17 so curved that, when in its operative position, it forms an accurate continuation of the inside curvature of the loop or engaging member 10. As the filler 16 is generally trapezoidal in shape, its sides 18 converge toward the ends 10' of the loop as well as toward the handle 14. Since the portions 10'' of the loop curve there, a slight separation is present between the sides 18 of the filler and the portions 10'' of the loop, particularly adjoining the curved end 17 of the filler. The spaces thus occurring between the filler 16 and the portions 10'' of the loop are filled by the metal 19 of the weld by which the filler is secured within the crotch of the loop. Thus the filler 16 is permanently secured to the loop 10 and becomes substantially an integral and continuing part thereof and so braces its juncture with the handle 14 that any tendency to bend or distort under the strain of use is overcome and prevented.

To cooperate with the gripping flange 12 of the lug 11 in the attachment of the wrench to an accumulator section or half, as will be described, a sliding latch or movable gripping member 20 is mounted on the section 15 of the handle 14 in opposition to the lug 11. This latch at one of its ends is provided with a transverse enlargement 21 to bear against the adjoining surface of the section 15 of the handle and to space the body of the latch from the handle a distance substantially equal to the spacing of the gripping flange 12 from the loop or engaging member 10. The end of the latch 20, having the enlargement 21, is also provided with a laterally projecting pin 22 which projects into and through a slot 23 formed in one side of the section 15 of the handle 14. A bolt 24

pierces and projects from the latch 20 parallel to the pin 23 to operate not only in the slot 23 of the handle, but also in a companion and registering slot 25 in the opposite side of the section 15 of the handle to the slot 23. The outer and projecting extremity of this bolt is provided with a wing nut 26 which can be tightened to fix the latch 20 in its adjusted positions with respect to the handle and to the loop 10. To accommodate the bolt 24 the filler 16 is also provided with a slot 27 which, when the filler is permanently secured in its operative position, as shown in Fig. 4, registers with the slots 23 and 25 in the handle. This permits the sliding adjustment of the latch 20 toward or away from the loop or engaging member 10 after the loosening of the wing nut 26.

The latch 20 is transversely enlarged at its inner end to create a relatively wide head 28 for engagement over the flange 30 of the accumulator, as will be described.

In Figs. 6 and 7 is illustrated a pair of the present wrenches in use for the assembly or dismantling of an accumulator. This accumulator comprises two hemi-spherical halves 29 each of which is provided with an outstanding flange 30 adjacent the ultimate seam between the halves, where the hemi-spherical halves are threaded one into the other or are otherwise interengaged. These flanges 30 are perforated by a series of openings 31 equal in number to the pins 13 and spaced one from the other in agreement with the spacing of said pins.

To engage one half 29 of the accumulator, the wing nut 26 of a wrench, constructed in accordance with the present invention, is loosened whereby the latch 20 may be moved rearwardly along the section 15 of the handle 14 in a direction away from the loop or engaging member 10. The lug 11 is then placed over the edge of the flange 30 of the accumulator half 29 thereby positioning its gripping flange 12 against the outer face of the flange and securing that portion of the flange 30 between the gripping flange 12 and the engaging member or loop 10. By swinging the tool toward the flange 30 about the lug 11 the loop or engaging member 10 is moved to rest flush against the inner surface of the flange 30 and the pins 13 of the loop are projected into the corresponding openings in the flange. With the loop 10 so positioned the latch 20 can be moved forwardly so that its head 28 overlies the flange 30, at a point diametrically opposed to the lug 11 and its gripping flange 12. The tightening of the wing nut 26 then locks the latch 20 against movement with its head 28 resting over and bearing against the flange 30 whereby the latter is clamped between said head 28 and the loop or engaging member 10 as well as between the loop 10 and the gripping flange 12 diametrically opposed to the latch 20. Thus the present wrench is lockingly but releasably attached to one half 29 of the accumulator and can not be removed without first loosening the wing nut 26 and moving the latch 20 outwardly of the end portion 15 of the handle 14 from the engagement of its head 28 over the flange 30. An identical wrench is similarly attached to the opposite half 29 of the accumulator.

When the two identical wrenches are attached to the sections 29 of the accumulator, as aforesaid, the handles 14 of both wrenches may be gripped and moved relatively in opposite directions thereby rotating the halves 29 of the accumulator relatively. In this manner the accumulator can be dismantled with each half lockingly engaged by one of the wrenches. When it is desired to reassemble

semble the accumulator each of its halves or sections 29 is lockingly engaged by a wrench, whereupon they may be placed in cooperating position and relatively rotated to cause interengagement of their attaching means and the final assembly of the accumulator. The wrenches may then be removed. So long as a wrench is attached to a section 29 of an accumulator, its handle 14 constitutes a handle by which the section may be manipulated, handled or transported.

While the present invention is particularly designed for the assembly or dismantling of an accumulator as aforesaid, it may, by slight modifications and changes, be adapted to engage any comparative structure without departure from the spirit and scope hereof.

What is claimed is:

1. A spanner wrench comprising an engaging member consisting of a section of metal bent upon itself to form a loop having reverse bends adjacent its extremities thereby positioning its end portions in parallel juxtaposition, a hollow handle longitudinally slotted at one end and adapted for the reception and permanent attachment of said end portions of the loop, a filler interposed between and secured to the reverse bends aforesaid, one edge of said filler being curved to form an uninterrupted continuation of the inner edge of the loop, a latch mounted for sliding movement on the handle adjacent the engaging member, a pin attached to said latch and mounted for reciprocation in the slots of the handle whereby the latch may be removably projected over said filler, a lug affixed to and projecting transversely from said engaging member in diametrical opposition to said latch, a flange angularly disposed at the end of said lug to rest over and parallel to said engaging member, a series of spaced pins projecting from one face of the engaging members, and means for releasably locking the latch in its adjusted positions.

2. A spanner wrench comprising an engaging member consisting of a section of metal bent upon itself to form a loop having reverse bends adjacent its extremities thereby positioning its end portions in parallel juxtaposition, a hollow handle longitudinally slotted at one end and adapted for the reception and permanent attachment of said end portions of the loop, a filler interposed between and secured to the reverse bends aforesaid, one edge of said filler being curved to form an unin-

terrupted continuation of the inner edge of the loop, a latch mounted for sliding movement on the handle adjacent the engaging member, an enlargement at one end of said latch bearing on

- 5 the handle to space the opposite end of the latch from the handle and the engaging member, a pin projecting from said enlargement to reciprocate in the slotted end of the handle whereby the spaced end of the latch may be removably projected over said filler, a lug projecting laterally from the engaging member in opposition to said latch, a flange angularly disposed to said lug to rest parallel to one face of the engaging member and to be spaced therefrom by the lug a distance
- 10 substantially equal to the distance of the spaced end of the latch from the handle and filler, a series of spaced pins projecting from the engaging member in the direction of the lug, and means for fixing the latch against movement.
- 15 20 3. A spanner wrench consisting of an engaging member formed from a strip of metal medially bent to create a loop with the terminals of said strip extending outwardly from the loop as a continuation of a diameter thereof, a filler interposed between and secured to said terminals adjacent the loop, a latch slidably associated with said terminals and filler for adjustment relative to said member, means for securing said latch against movement in its adjusted position, and a
- 25 30 lug immovably affixed to the engaging member in diametrical opposition to the latch.
